UNITED STATES PATENT OFFICE.

BURNHAM C. STICKNEY, OF ELIZABETH, NEW JERSEY, AND ARTHUR A. JOHNSON, OF NEW YORK, N. Y., ASSIGNEES TO UNIWERWOOD TYPEWRITER COMPANY, OF NEW YORK, N. Y., A CORPORATION OF DELAWARE.

TYPE-WRITING MACHINE.

1,295,383.

Specification of Letters Patent. Patented Feb. 25, 1919.

Application filed October 27, 1917. Serial No. 193,759.

To all whom it may concern:

Be it known that we, BURNHAM C. STICKNEY and ARTHUR A. JOHNSON, both citizens of the United States, said STICKNEY residing 5 in Elizabeth, county of Union, and State of New Jersey, and said JOHNSON residing in borough of the Bronx, county of the Bronx, city and State of New York, have invented certain new and useful Improvements in 10 Type-Writing Machines, of which the following is a specification.

This invention relates to typewriter collating devices, in which work-sheets are assembled or superposed in various relations 15 preparatory to typewriting thereon. One of the advantages of the invention is that the work-sheets may be collated without the necessity of employing studs, and hence without the necessity of perforating the 20 sheets for engagement with the studs; and the device is further capable of use with quite a large number of collating sheets.

In the K'Burg Patent No. 1,259,630, of March 19, 1918, the work-sheets are illustrated as inserted individually, by means of a chute provided at the rear of the platen; although many of the features of the present invention may be employed in machines in which no chute is used. In said K'Burg 30 patent, the sheets one at a time are conducted by the chute around under the platen and up in front thereof, and their leading edges are positioned upon an assembling or collating table arranged at the delivery side 35 of the platen, the leading edges of the sheets being thus located in various relative positions, or collated.

According to the present improvements, as each work-sheet is positioned upon the 40 collating table, it may be detained in such position by means of the first of a succession of clip devices, while another sheet is being superposed upon the first and positioned relatively thereto; whereupon the second 45 sheet may also be clipped by the second clip device, and a third sheet may be superposed upon the second and then clipped by a third clip, and so on; the relative positioning of all the sheets being maintained throughout 50 the collating operation, without the necessity of resorting to perforations or studs. The clips may be arranged in a row at one or both sides of the collating table.

At the collating table there is provided 55 a gage, which enables the operator to locate

accurately the superposed work-sheets one by one as they are collated; each sheet being positioned with reference to said gage, which is common to all the sheets, so that the sheets will have proper relative adjustment 60 while they are thereafter moved as a unit around the typewriter platen to the proper position to begin the first line of writing thereon; such relative positioning being preserved throughout the typewriting operation. 65

After once being clipped, the sheets are not given opportunity to become relatively disarranged, because they are always kept together either by the clips or by the feed 70 rolls which usually run upon the typewriter platen. These feed rolls stand released during the collating operation, but are restored to normal positions before the sheets are released from the control of the clips. The 75 clips are so formed and mounted that they may be readily moved to sheet-releasing positions; and preferably they maintain themselves mechanically in either released or working positions. All the clips may be 80 connected for a simultaneous release of the sheets; and this releasing device may be connected to a device that restores the rolls to the typewriter platen, so that a single 85 operation will release the sheets from the clips, and place them under control of the platen feed rolls just before the sheets are released from the bite of the clips. The 90 clips are so placed upon the collating board that the sheets while held by the clips extend therefrom around the under side of the platen to position to be gripped by the feed rolls, preparatory to backing the sheets down to bring the first line thereon to the writing 95 point.

Other features and advantages will hereinafter appear.

In the accompanying drawings,

Figure 1 is a perspective view of the platen and the collating device attached to 100 the platen. This view shows three sheets, ledger, statement and invoice sheets, in their collated or assembled positions on the platen, with clips for temporarily holding them in position.

Fig. 2 is a side view in elevation, with all 105 of the clips thrown out of action.

Fig. 3 is a detail perspective view, showing one of the work-sheet clips in action.

Fig. 4 is a front view in elevation, partly 110

broken away to show the underlying structure. Some of the clips in this view are in their active positions, but most of them are in their inoperative raised positions.

Fig. 5 is a side view, in section, taken from front to rear, showing all of the clips in action.

A platen 1 is mounted to rotate on a carriage 2 in a manner common to Underwood 10 standard typewriters. This platen may be rotated in the usual manner, either by hand-knobs 3, or by line-space mechanism represented generally by the line-space wheel 4.

The work-sheets are gripped to the platen 15 1 by means of pressure feed-roll mechanism, only a part of which is shown. This feed-roll mechanism includes rollers 5 mounted on shafts 6, only one of which is shown, which, in turn, are mounted on levers 7, 20 which are provided with arms 8, which engage the flat sides of a rock shaft 9. Normally, the rock shaft 9 is in the position of Figs. 2 and 5, with the arms 8 nearest the axis of the rock shaft 9. This corresponds 25 to the position of the pressure feed rolls 5 in active engagement with the work-sheets on the platen 1, whereby the work-sheets will be fed evenly with the rotary feeding movement of the platen. The rock shaft 9 30 can be turned around its axis to force the arms 8 farther from the center of the rock shaft 9, thereby withdrawing the pressure feed rolls 5 against the tension of the springs (not shown) from their active relation with 35 respect to the platen 1. The rock shaft 9 is rocked by means of an arm 10 connected by a link 11 to a release lever 12. This is the usual standard Underwood pressure feed-roll mechanism, and is briefly described, since its action is, in a way, coöperative with the action of the collating device.

A chute 13, extending to the platen 1 at the rear or introductory side thereof, and conforming in its slope to the paper-apron 14, may in many cases be employed on the carriage 2. This chute 13 may be formed in two sections, having a pin-and-slot connection 14^a with each other, so as to expand and collapse to accommodate 45 work-sheets of different widths. The chute 13 may have sides 15, to act as gages and guides for the sides of the work-sheets.

The chute 13 may extend down around the under side of the platen 1 at 16, to 50 direct the work-sheets around to the front of the platen. This portion 16 of the chute 13 is provided with straps 17, which extend up over the front of the platen, where they are connected to the sides 15 by extensions 55 18 of these sides, and thus to the body of the chute 13. Thus the work-sheets may be guided as they are inserted in the chute 13 up around the platen 1 to a position such that their leading edges are located at the 60 front of the platen and above the same.

The work-sheets, as indicated in Fig. 1 are collated upon a table 19, which is fixed relatively to the platen at the delivery side thereof.

This table may be provided with a gaging bar 20, to extend parallel to the axis of the platen 1, and having a sliding connection with the table 19, so as to permit a transverse adjustment between the table and the bar 20 and accommodate the expansion and contraction of the table. The bar 20 provides an edge with which the first line to be written on of the several sheets may be brought into register, each sheet passing up between this register bar and the platen 80 or the collating table.

The table 19 may be formed in two sections, mounted for relative sliding movement on a bar 21, and having pin-and-slot connections 22 with each other, to be adjustable to accommodate work-sheets of different widths.

The table 19 forms a support upon which the leading ends of the work-sheets can be rested. Additional means is provided for 90 clipping or holding each sheet on the table, so that the operative can have the use of both hands in assembling the next sheet. For this purpose, there is provided at each side of the table 19 a series of clips 22, 95 whose preferred form is more particularly shown in Fig. 3. These clips are mounted upon pivots 23, about which they may rotate from erect positions preferably in substantially vertical planes to recumbent positions against or parallel with the table 19. In the latter positions the clips or clamps 22 bring roughened surfaces 24 thereon in engagement with the work-sheets resting on the table 19. As there are several of these 100 clips 22 located at different levels, they may be used to secure individual work-sheets in position upon the platen 1 and upon the table 19.

The table 19 may have side gages 25 110 which may be rabbeded or grooved at 26 to receive the clips 22, so that when they are in their inactive positions, they will be flush with the inner faces of the side gages 25, or they may stand just outside thereof. 115 In this way they will not obstruct the movement of the work-sheets, either in assembling them or in a normal typewriting operation.

The clips 22 may be held in their active 120 and inactive positions by springs 27, one to each clip. These springs engage inclined surfaces 28 provided on each of the clips. When the clips are swung to their vertical inactive positions, the springs 27 engage 125 the ends of the ridges 29, which form the inclined surfaces 28.

To facilitate or simplify the use of the device, the clips 22 may be thrown out together, to enable the sheets to advance or to 130

be fed backwardly around the platen; that is to say, all of the clips on each side may be disengaged from the work-sheets by a common release. For this purpose, each of 5 them is provided with a projection 30, which extends beyond the sides 25 of the table 19. These projections 30 underlie a releasing rail 31, on provided on each side of the table 19. These releasing rails 10 have inclined slots 32, which engage pins 33, secured to the sides of the table 19. Each rail 31 is actuated by a common handle 34 against the tension of a spring 35, so that as the rail moves lengthwise, the cam 15 slots 32 will also force it to move transversely with respect to its length, whereby it will engage the projections 30 and rock the clips 22 so as to raise them in unison from their active positions, indicated in 20 Fig. 3, to their inactive positions, shown in Fig. 2.

The utility of the device will be readily understood when taken in connection with the above description. In the example 25 shown, there are provided ledger, statement and invoice sheets. The feed rolls 5 are first released. Then the ledger sheet is inserted, top edge first, at the rear of the platen 1 through the chute 13. Its leading 30 edge is drawn up on the table 19, until the next blank line to be typewritten upon is in register with the upper edge of the gage-rail 20. Opposite top side clips 22 (which will engage with the top of the 35 ledger sheet, as it is shown to be the highest of the three sheets) are brought in play, clipping the ledger sheet to the table 19. However, the sheet may in some cases be held by a single clip. The operative 40 then has both of his hands free to introduce and collate the other work-sheets in succession. The statement sheet is positioned upon the platen after the insertion of an interleaving carbon sheet, and is 45 brought to a position with its next line to be typewritten upon in register with the guide-bar or rail 20. Then it is held on the table 19 by means of the next lower opposite clips 22. The invoice sheet is then 50 positioned in the same manner, with the carbon sheet between it and the statement sheet. This sheet may also be secured to the collating table 19 by means of the third opposite clips 22. It is obvious that the 55 clips may be used in any order. Since each clip is of thin plate-like or leaf-like form, it lies conveniently between the sheets if required.

The feed rolls 5 are then brought into 60 play by an operation of the release key-lever 12, so that the assembled work-sheets are gripped to the platen 1, in their collated position, forming a set. The series of clips on both sides of the collating table can now 65 be released by an operation of the handle 34

on the right-hand bar 31, which is connected by an extensible rod 31^a with the left-hand bar 31. Each of these bars will swing all of the clips on the corresponding side of the collating table 19 simultaneously to inactive positions. If any clip underlies a sheet, it will readily clear itself therefrom, being made short and of simple form for this purpose. 70

The collated pack of sheets can then be 75 fed backwardly by a reverse rotation of the platen 1, so as to bring the superposed lines, which were brought into register with one of the edges of the guide-rail 20, into register with the printing point of the typewriting machine indicated by a type-bar 36 striking the platen 1 (Figs. 1 and 2). The normal typewriting operation can then take place. All of the clips 22 will have their 80 faces flush with or outside of the sides 25, so that they will not interfere with the movement of the work-sheets as they are advanced during a typewriting operation.

The feed-roll release mechanism may be 85 connected to the handle 34 so that when the handle is operated to move the clips 22 to ineffective position, the rolls 5 will be set against the platen to hold the sheets against the platen. This may be done before the rails 31 move the clips off from the sheets. 90

For this purpose, the connections between the handle 34 and the feed-roll release mechanism may comprise a sleeve 35^a secured to the usual arm 37 which is connected by link 11 to rock the shaft 9. Extending into said 100 sleeve 35^a and connected to move therewith by a pin 38 is a shaft 39, to the other end of which is connected an arm 40. The arm 40 is connected by a link 41 to an extension 42 upon the right-hand rail 31. The link 41 105 has a pin-and-slot connection 44, 45, with said rail 31, so that the feed rolls may be released by the operation of the key 12 without affecting the clips, and so that the 110 clips may be released without casting the feed rolls off the platen. When, however, the feed-roll release lever is in position to hold the rolls off from the platen, as during collating, and the handle 34 is operated, the 115 pin 44 will engage the end of the slot 45, and, through the connections described, rock the shaft 9 to set the feed rolls against the platen. The sleeve 35^a has a slot into which 120 extends the pin 38 on the shaft 39, to permit adjustment of the chute in which the shaft 39 is mounted, without interrupting the connections between the handle 34 and the feed-roll release mechanism.

Each section of the table 19 is secured by means of an ear 46 to an arm 47 slidably 125 mounted on a rod 48, extending across the typewriter carriage and mounted in the end plates 2 thereof. The upper end of the arm 47 is forked to engage the supporting rod 21 mounted in a bracket 49 secured to each 130

of the side plates 2. Thus, by means of the rod 21 and the rod 48 the arm 47 and the section of the paper table carried thereby are held against all but sliding movements longitudinally of the machine. The arm 47 is secured to a boss 50 which is formed upon the sides 15 of the chute 13. Therefore, one section of the chute 13 and a corresponding section of the table 19 are secured together for sliding movement along the typewriter carriage, for the purpose of adjusting the device, particularly the clips 22, to accommodate different classes of work, this movement being permitted by the extensible or telescoping rod 31 which connects the release rails 31 for simultaneous operation.

The sections of the table and chute are held against movement relatively to one another by means of screws 51 which pass through slots 22^a of the right-hand section of the table 19, the screws being threaded into a portion of the left-hand section of the collating table 19. When the sections of the chute are moved to and from one another, the feed rolls 5, which are slidably mounted upon the shaft 6, move with said sections because of the engagement of the feed rolls with the side edges 52 of openings in the chute provided for the feed rolls. A screw 52 may be provided upon the ends of the shaft 6, to prevent accidental removal of the feed rolls from the shaft.

The gaging bar 20 is of such length as to prevent its removal from the slots 20^a in the side edges of the paper table, when the table is fully expanded. The gage bar is made of springy material and is frictionally held in slots 20^a because of the curvature of the slots.

Variations may be resorted to within the scope of the invention, and portions of the improvements may be used without others.

Having thus described our invention, we claim:

1. The combination with a platen and a roll to run thereon, of a relatively fixed collating table coöperating with said platen at the delivery side thereof, to enable the assembling of sheets thereon while extending between said roll and platen, and a row of contact slips to engage sheets in assembling them on said table to hold the sheets against edgewise movement, said slips releasable with respect to said sheets, to permit said sheets to be withdrawn by said platen and roll from the collating table to the typewriting starting position with the same relative arrangement as assembled on said table, said row extending in the direction of travel of the sheets.

2. The combination with a platen, of a collating table coöperating with said platen to collate work-sheets on said platen, a series of slips adjustable to be brought into indi-

vidual action to grip work-sheets to said collating table, and a common means for silencing a plurality of said slips in unison.

3. The combination with a platen, of a table for collating work-sheets on said platen, said table having sides to guide the sheets, and a plurality of clips to hold work-sheets on said table as collated, said sides being rabbeted to receive said clips when in their inactive positions, so that said clips will be included in said sides with the exposed surfaces thereof withdrawn at least flush with the surfaces of said sides, whereby said table and said clips will afford a free and clear passage to the work-sheets coming from said platen onto said table.

4. The combination with a platen, of a table for collating work-sheets on said platen, said table having sides to guide the sheets, a series of independently releasable clips mounted on said table and occupying a position parallel to said table when in action, said clips having projections extending beyond the sides of said table, and shift rails each common to a series of said clips and overlying said projections beyond the sides of the table, so as to move a series of said clips to their inactive positions in unison.

5. The combination with a platen, of a table coöperating with said platen to collate work-sheets thereon, a series of clips extending parallel with the bottom of said table when in action, springs for holding said clips in their active and inactive positions, each of said clips having a ridge with an inclined surface engaged by said spring, so as to hold said clips in their active and inactive positions, and a rail for a series of said clips having a combined longitudinal and transverse movement to withdraw said clips to their inactive positions.

6. The combination with a platen, of a table coöperating with said platen to collate work-sheets on said platen, a series of flat clips arranged at the side of said collating table to clip work-sheets smoothly upon said table, said clips extending close to the bottom of said table when in action and in the path of movement of said work-sheets, and means for shifting said clips to position clear of the path of movement of said work-sheets, said table being rabbeted to receive said clips within the confines of the body portion thereof.

7. In a typewriting machine, the combination with a platen and a paper-feeding device bearing upon the same, of a collating board at the delivery side of the platen, a clip device to hold the work upon the collating board while the work extends between the platen and the feeding device, and a manually operable member common to said clip and said feeding device for both releasing the clip and restoring the feeding device against the platen or the work thereon.

8. In a typewriting machine, the combination with a platen and a paper-feeding device bearing upon the same, of a collating board at the delivery side of the platen, a clip device to hold the work upon the collating board while the work extends between the platen and the feeding device, and a manually operable member common to said clip and said feeding device for both releasing the clip and restoring the feeding device against the platen or the work thereon, and effective to restore the feeding device in advance of the release of the work from the control of the clip device.

15 9. In a typewriting machine, the combination with a platen and a paper-feeding device bearing upon the same, of a collating board at the delivery side of the platen, a clip device to hold the work upon the collating board while the work extends between the platen and the feeding device, a manually operable member common to said clip and said feeding device for both releasing the clip and restoring the feeding device against the platen or the work thereon, and effective to restore the feeding device in advance of the release of the work from the control of the clip device, and a key being also provided for casting off and restoring the feeding device independently of the clip device.

10. In a typewriting machine, the combination with a platen and a paper-feeding device bearing upon the same, of a collating board at the delivery side of the platen, a clip device to hold the work upon the collating board while the work extends between the platen and the feeding device, and a manually operable member common to said clip device and said feeding device for both releasing the clip device and restoring the feeding device against the platen or the work thereon, and effective to restore the feeding device in advance of the release of the work from the control of the clip device, said clip device being operable to hold and release the work independently of the feeding device.

11. The combination with a revolvable platen, a feed device to bear thereon, and a collating board arranged at the delivery side of the platen, of a clip to hold the work stationary upon the collating board while the work extends between said platen and said feed device, and releasable to release the work so that the latter may be controlled by the feed device and platen, and a second work-holding clip arranged between the first clip and the platen, and releasable independently of the first clip.

12. The combination with a revolvable platen, a feed device to bear thereon, and a collating board arranged at the delivery side of the platen, of a clip device to hold the work upon the collating board, and releasable to release the work so that the latter may

be controlled by the feed device and platen, said clip device comprising a plurality of independently operable clips.

13. The combination with a revolvable platen, a feed device to bear thereon, and a collating board arranged at the delivery side of the platen, of a clip device to hold the work upon the collating board, and releasable to release the work so that the latter may be controlled by the feed device and platen, said clip device comprising clips upon opposite sides of the board, and over which clips the work may be collated.

14. The combination with a revolvable platen, a feed device to bear thereon, and a collating board arranged at the delivery side of the platen, of a clip device to hold the work upon the collating board, and releasable to release the work so that the latter may be controlled by the feed device and platen, said clip device comprising a plurality of independently operable clips at each side of the collating board.

15. The combination with a revolvable platen, a feed device to bear thereon, and a collating board arranged at the delivery side of the platen, of a clip device to hold the work upon the collating board, and releasable to release the work so that the latter may be controlled by the feed device and platen, said clip device comprising a row of independently operable clips at each side of the board, and means common to said clips to release them by a single operation.

16. The combination with a revolvable platen, a feed device to bear thereon, and a collating board arranged at the delivery side of the platen, of a clip device to hold the work upon the collating board, and releasable to release the work so that the latter may be controlled by the feed device and platen, said clip device comprising a plurality of clips at each side of the collating board, and a single device common to all of the clips upon the collating board and operable to cast off all of said clips.

17. The combination with a revolvable platen, a feed device to bear thereon, and a collating board arranged at the delivery side of the platen, of a clip device to hold the work upon the collating board, and releasable to release the work so that the latter may be controlled by the feed device and platen, said clip device comprising a finger mounted upon the collating board, and having the form of a flat plate movable into and out of position to clip the sheet, and to constitute a thin leaf between the clipped sheet and a superposed sheet, whereby collating of a superposed sheet overlying the clip is permitted.

18. The combination with a revolvable platen, a feed device to bear thereon, and a collating board arranged at the delivery side of the platen, of a clip device to hold the

- work upon the collating board, and releasable to release the work so that the latter may be controlled by the feed device and platen, said clip device comprising independently operable clip fingers mounted upon opposite sides or ends of the collating board, and each having the form of a flat plate movable into and out of position to clip the sheet, whereby said clips may form thin leaves between superposed sheets.
19. The combination with a revoluble platen, a feed device to bear thereon, and a collating board arranged at the delivery side of the platen, of a clip device to hold the work upon the collating board, and releasable to release the work so that the latter may be controlled by the feed device and platen, said clip device comprising independently operable clip fingers mounted upon opposite sides or ends of the collating board, and each having the form of a flat plate movable into and out of position to clip the sheet, whereby said clips may form thin leaves between superposed sheets, said 25 clips in the form of pivoted fingers extending inwardly from the edge of the collating board, and shortened to readily clear a superposed sheet when the clip is swung up.
20. The combination with a revoluble platen, a feed device to bear thereon, and a collating board arranged at the delivery side of the platen, of a clip device to hold the work upon the collating board, and releasable to release the work so that the latter may be controlled by the feed device and platen, said clip device comprising independently operable clip fingers mounted upon opposite sides or ends of the collating board, and each having the form of a flat 30 plate movable into and out of position to clip the sheet, whereby said clips may form thin leaves between superposed sheets, said 35 clips in the form of pivoted fingers extending inwardly from the edge of the collating board, and shortened to readily clear a superposed sheet when the clip is swung up, each of said clips mounted to bear directly upon the collating table independently of the others.
21. In a typewriting machine, the combination with a platen and paper-feeding devices bearing upon the same, of a collating board at the delivery side of the platen, a clip device to hold the work upon the collating board while the work extends between the platen and the feeding devices, said clip device comprising clips at each side of the collating board, and means whereby the clip devices on each side of the board may be adjusted to and from one another.
22. In a typewriting machine, the combination with a platen and paper-feeding devices bearing upon the same, of a collating board at the delivery side of the platen, and 55 a clip device to hold the work upon the

collating board while the work extends between the platen and the feeding devices, said clip device comprising clips at each side of the collating board, said clip device at each side of the collating board being adjustable to and from the opposite clip device.

23. In a typewriting machine, the combination with a platen and paper-feeding devices bearing upon the same, of a collating board at the delivery side of the platen, and a clip device to hold the work upon the collating board while the work extends between the platen and the feeding devices, said clip device comprising clips at each side of the collating board, said clip device being mounted for adjustment longitudinally of the machine.

24. In a typewriting machine, the combination with a platen and paper-feeding devices bearing upon the same, of a collating board at the delivery side of the platen, collating devices to hold the work upon the collating board while the work extends between the platen and the feeding devices, and a gage on said board extending across the same and beneath which the work-sheets extend as they are collated.

25. In a typewriting machine, the combination with a platen, a feed roll to run thereon, and a collating table at the delivery side of the platen, of a releasable work-holding clip for holding a sheet against endwise movement on said table, an independently releasable clip arranged at a point nearer the platen than the first clip, and means to release said clips simultaneously.

26. In a typewriting machine, the combination with a platen, a feed roll to run thereon, and a collating table at the delivery side of the platen, of a releasable work-holding clip for holding a sheet against endwise movement on said table, an independently releasable clip arranged at a point nearer the platen than the first clip, and means to release said clips simultaneously; one of said clips arranged at one side of said table, and the second of said clips arranged at the opposite side of said table.

27. In a typewriting machine, the combination with a platen, a feed roll to run thereon, and a collating table at the delivery side of the platen, of a plurality of independently releasable clips to coöperate with said collating table to clip the work-sheets one by one as they are collated on the table, and means common to said clips to release them simultaneously.

28. In a typewriting machine, the combination with a platen and a paper-feeding device bearing upon the same, of a collating board at the delivery side of the platen, a clip device to hold the work upon the collating board while the work extends between the platen and the feeding device, a manu-

ally operable member common to said clip and said feeding device for both releasing the clip and restoring the feeding device against the platen or the work thereon, and 5 a key having means for casting off and restoring the feeding device independently of the clip device.

29. In a typewriting machine, the combination with a revoluble platen, of a collecting board mounted at the delivery side 10 of the platen and comprising relatively ad-

justable parts whereby the board is rendered extensible, releasable work clips mounted upon each of said relatively adjustable parts, and a common releasing device for all of said clips. 15
